US00D776942S

(12) **United States Design Patent** (10) **Patent No.:** **US D776,942 S**
(45) **Date of Patent:** ** *Jan. 24, 2017

(54) **DISPLAY BASE**

(71) **Applicant:** **3M INNOVATIVE PROPERTIES COMPANY**, St. Paul, MN (US)

(72) **Inventors:** **Judd D. Olson**, Deephaven, MN (US); **Thomas W. Floyd**, St. Paul, MN (US); **Kevin E. Kinzer**, Forest Lake, MN (US); **Stephan A. Hawthorne**, St. Paul, MN (US); **Sandra K. Nowak**, St. Paul, MN (US); **Irina Hass**, Woodbury, MN (US); **Linda W. Suszko**, Stillwater, MN (US)

(73) **Assignee:** **3M INNOVATIVE PROPERTIES COMPANY**, St. Paul, MN (US)

(*) **Notice:** This patent is subject to a terminal disclaimer.

(**) **Term:** **14 Years**

(21) **Appl. No.:** **29/521,058**

(22) **Filed:** **Mar. 19, 2015**

(51) **LOC (10) Cl.** **06-07**

(52) **U.S. Cl.** **USPC** **D6/300**

(58) **Field of Classification Search**

(57) **CLAIM**

The ornamental design for a display base, as shown and described.

DESCRIPTION

FIG. 1 is a perspective view showing the new design for a display base;

FIG. 2 is a front view thereof;

FIG. 3 is a rear view thereof;

FIG. 4 is a right side view thereof, a left side view being a mirror image; and

FIG. 5 is a top view thereof, a bottom view being a mirror image;

FIG. 6 is a perspective view of a second embodiment showing the new design for a display base;

FIG. 7 is a front view thereof;

FIG. 8 is a rear view thereof;
FIG. 9 is a right side view thereof, a left side view being a mirror image; and
FIG. 10 is a top view thereof, a bottom view being a mirror image;
FIG. 11 is a perspective view of a third embodiment showing the new design for a display base;
FIG. 12 is a front view thereof;
FIG. 13 is a rear view thereof;

FIG. 14 is a right side view thereof, a left side view being a mirror image; and
FIG. 15 is a top view thereof, a bottom view being a mirror image.

The portions of the display base in FIGS. 1-15 shown in broken lines are included to show features that form no part of the claimed design.
